HUGO SEROG, OF VIENNA, AUSTRIA

PLANE-GRAVE FURNACE

Application filed January 26, 1929, Serial No. 335,304, and in Austria February 24, 1928.

Furnaces in which a steam body substantially pyramidal in shape is maintained above the grate surface are known. In case of long plane grates the difficulty may arise 5 that the steam jets of the steam pyramid which form the top steam layer and extend nearer to the fire bridge are atomized in their last part and are no more efficient enough for preventing the hot gases rising from the 10 grate in the proximity of the fire bridge from directly escaping over the fire bridge. In case of long grates this results in that the hot gases may partly escape through the weakened layer of steam in the proximity 15 of the fire bridge and cannot be mixed with the cooler gases rising from the front part of the grate; also part of the cooler gases drawn forward by the steam jets may escape near the fire bridge through the thin steam 20 layer. By these facts the desired smokelessness is interfered with and the heating effect to be secured by the steam pyramid is considerably reduced since the mixture of the hot gases with the cooler front gases cannot 25 take place to the desired extent.

With a view of overcoming these difficulties the present invention consists in providing a set of steam nozzles for forming a substantially pyramid shaped steam body above 30 the grate having its apex in the proximity of the fire door and above the plane of the grate, such pyramid shaped steam body having sides diverging from the said apex towards the grate and the fire bridge in combination 35 with means for producing a steam layer located above the top side of the said pyramidal steam body by steam jets issuing from nozzles located in the proximity of the fire bridge and above the plane of the grate such 40 steam jets converging to a point in the proximity of the fire door and above the plane of the grate.

The annexed drawings illustrate by way of 45 example two constructional forms of the invention.

Fig. 1 is a longitudinal section of a furnace according to the invention in a fire tube boiler. Fig. 2 is a part of a plane view of Fig. 1. Fig. 3 is a longitudinal section of a modified 50 constructional form of a furnace for a water

tube boiler and Fig. 4 is a plan view of Fig. 3.

In the furnace chamber 10, Figs. 1 and 2 of a plane grate boiler furnace the plane grate 8 is supported at one end at the fire door wall 11 and at the other end at the fire bridge 55 9. Above the fire door a nozzle set D having a plurality of nozzle holes is provided, such nozzle holes having diverging axes coinciding with the axes of the steam jets and intersecting the grate plane at the points 4, 5 and 6. These steam jets form the part of the steam pyramid near the fire door. At the points 1, 2 and 3 nozzles are provided in the nozzle set D' on the fire bridge 9. The axes 60 of the nozzles 1, 2 and 3 converge towards the nozzle set D. Moreover a steam jet 7 issues horizontally from the fire bridge into the furnace chamber.

The effect of this arrangement consists in 70 that the steam layer produced by the steam jets 1, 2 and 3 issuing from the fire bridge is spread as a protective shield over the hot gases rising from the rear part of the grate and is at this part, of such a strength, 75 that the hot gases cannot penetrate any more through this dense layer and escape directly above the fire bridge, but are deflected towards the front where they can mix with the smoke gases supplied from the bottom part 80 of the steam pyramid. The fact, that the jets 1, 2 and 3 of this new steam pyramid are oppositely directed to the steam jets 4, 5 and 6 and thereby produce a draught opposite to that produced by the steam jets 4, 5 and 6, is 85 not objectionable since the jets 1, 2 and 3 cannot exert an intense draught action at the point where they come near the jets 4, 5 and 6 because they are atomized in their last part owing to the length of the grate and cannot at this part overcome the intense draught 90 due to the jets 4, 5 and 6.

In view of the above the draught conditions are the following:

The steam jets 1, 2 and 3 lead the hot gases 95 to the cooler burning gases carried by the jets 4, 5 and 6. Besides for securely guiding the hot gases a steam jet 7 is so provided below the steam jets 1, 2 and 3 that it extends centrally below the steam layer formed by the steam jets 1, 2 and 3. The intensity of the 100

steam jets 1, 2, 3 and 7 is so selected that a disturbance of the draught action exerted by the steam jets 4, 5 and 6 cannot take place. The hot gases carried by the jets 1, 2, 3 and 5 7 are reversed by being mixed with the cooler smoke gases carried by the jets 4, 5 and 6 owing to the intense draught action of the jets 4, 5 and 6 at the point where they meet, and thus are brought into the centre of the 10 pyramid, where an intimate mixture may take place. Owing to this intimate mixture the combustion is a much more complete one than was possible below the ordinary steam pyramid because the mixing is accompanied 15 by eddies in the gases caused by the opposite draught actions and this method of mixing the gases takes place in a much more efficient manner below the steam pyramid.

In this furnace the steam jets nearer to the 20 fire bridge are blown in directions converging towards the starting point of the steam jets entering above the fire door. This is suitable more particularly for flue boilers on account of the low height of the furnace, but 25 shows some drawback in furnaces of a greater height such as for instance in water tube boiler furnaces.

In water tube boilers, having naturally 30 greater grate surfaces on which much greater quantities of fuel are consumed per unit of time, the short way of the gases resulting from the steam pyramid is not sufficient to bring about an intimate mixture of gases with the top air and consequently a reduction 35 of the development of smoke is secured, but not the complete consumption of the smoke. It is an object of the present invention to secure this and this object is attained by an arrangement in which the 40 steam jets coming from the fire bridge are not directed towards the starting point of the steam jets coming from the fire door wall, but form a converging steam layer being directed towards the fire door wall above 45 the pyramid shaped steam body maintained over the grate surface.

10, Figs. 3 and 4, is again the furnace chamber of a water tube boiler. The plane grate 8 is supported by the fire door wall 50 11 and the fire bridge 9. Steam jets 1, 2, 3, 4, 5, 6 are blown from the nozzle head D located above the fire door, the axes of these steam jets diverge and the steam jets form a steam body above the grate surface. 55 At the points 70, 80, 90, 100 nozzles D' are provided. From these nozzles steam jets are blown which are located above the steam body formed by the steam jets 1 to 6, and converge towards the fire door wall. The 60 hot gases rising from points near to the fire bridge below the jets 1, 2 and 3 which have already lost a considerable part of their strength, are caught by the steam jets 70, 80, 90, 100 having the greatest strength near 65 the fire bridge and are carried towards the

fire door and as they are so carried they are intimately mixed with the cooler gases and the top air between the steam jets 1 to 3 and 70, 80, 90, 100 flowing in opposite directions. The gases thus completely burnt 70 then again meet above the steam layer and flow in a vertical direction towards the water tubes heating the latter. Thereby an undue heating of the brick walls and vaults is avoided and the heat losses due to radiation 75 are reduced.

What I claim is:

1. In a plane grate furnace comprising a plane grate, a fire door at one end of the grate and a fire bridge at the opposite end of the 80 grate a set of steam nozzles in the proximity of the fire door and above the plane of the grate adapted to produce steam jets forming a steam body substantially in the shape of a pyramid having its apex in the said set of steam nozzles the said steam jets diverging towards the fire bridge and the plane of the fire grate in combination with a plurality of steam nozzles located in the proximity of the fire bridge and above 85 the plane of the fire grate and adapted to project steam jets converging towards a point in the proximity of the fire door and above the plane of the grate and located in a plane above the top surface of the said steam body 90 substantially pyramidal in shape.

2. In a plane grate furnace comprising a plane grate, a fire door at one end of the grate and a fire bridge at the opposite end of the 100 grate a set of steam nozzles in the proximity of the fire door and above the plane of the grate adapted to produce steam jets forming a steam body substantially in the shape of a pyramid having its apex in the said set of steam nozzles the said steam jets diverging towards the fire bridge and the plane of the fire grate in combination with a plurality of steam nozzles located in the proximity of the fire bridge and above 105 the plane of the fire grate and adapted to project steam jets converging towards the apex of the said pyramid and located in a plane above the top surface of the said steam body 110 substantially pyramidal in shape.

3. In a plane grate furnace comprising a plane grate, a fire door at one end of the grate and a fire bridge at the opposite end of the 115 grate a set of steam nozzles in the proximity of the fire door and above the plane of the grate adapted to produce steam jets forming a steam body substantially in the shape of a pyramid having its apex in the said set of steam nozzles the said steam jets diverging towards the fire bridge and the plane of the fire grate in combination with a plurality of steam nozzles located in the proximity of the fire bridge and above 120 the plane of the grate and adapted to project steam jets converging towards the apex of the said pyramid and located in a plane 125 above the top surface of the said steam body 130 substantially pyramidal in shape.

above the top surface of the said steam body substantially pyramidal in shape and with an additional nozzle located in line with the said plurality of steam nozzles located in the proximity of the fire bridge and above the plane of the grate such nozzle being adapted to project a steam jet towards the fire door and parallel to the plane of the grate.

10 In testimony whereof I have affixed my signature.
